WILLIAM D. LUTZ, OF ALLENDALE BOROUGH, NEW JERSEY, ASSIGNOR TO OTIS ELEVATOR COMPANY, OF JERSEY CITY, NEW JERSEY, A CORPORATION OF NEW JEPSEY.

ELECTROMAGNET.

1,132,783.

Specification of Letters Patent. Patented Mar. 23, 1915.

Application filed August 19, 1912. Serial No. 715,704.

To all whom it may concern:

Be it known that I, WILLIAM D. LUTZ, a citizen of the United States, residing in the borough of Allendale, in the county of Bergen and State of New Jersey, have invented a new and useful Improvement in Electromagnets, of which the following is a specification.

My invention relates to electromagnets adapted for use with alternating currents.

An object of the invention is to provide simple and reliable means for overcoming or preventing residual magnetism.

My invention is herein illustrated as applied to an alternating current magnet especially designed to operate a brake for an elevator, although it will be understood that the invention may have a much more general application.

A serious drawback to the use of alternating current electric elevators has been the inability to secure a reliable and efficient alternating current brake magnet. In order to prevent an excessive current being consumed in magnets of this type, it is necessary to provide a magnetic path of low resistance, so that the magnetic flux will be sufficient to choke back the current. To accomplish this it is customary to arrange the pole faces of the magnet, or the magnet and its armature so that they will be held in intimate contact while the magnet is excited, thereby forming a practically continuous iron circuit for the magnetic lines of force. Such a magnet is uncertain in operation and unreliable owing to liability of the pole faces to hold together or "stick" on account of the residual magnetism after the current supply has been cut off. The amount of this residual magnetism varies greatly in any given magnet, and depends on the strength and direction of the energizing current at the instant the circuit is opened. Careful tests of brake magnet of this type designed for elevator service have demonstrated that in the same magnet the holding power due to residual magnetism may vary from zero up to practically the full holding power of the magnet. In other words the force required to separate the magnet pole faces after the current has been

cut off may be nearly equal to that required to separate them when the magnet is receiving full current. Owing to this liability of the residual magnetism to assert itself at any time, such magnets have proved unreliable in practice. When used as brake magnets to hold the brakes off they have been the cause of serious accidents, by preventing the brakes from being applied when the current is cut off. Attempts have been made to overcome the above defect by interposing a thin layer of non-magnetic material between the pole faces of the magnet. Such an expedient, however, has proved unsatisfactory as it not only increases the consumption of current but weakens the magnet and also renders it excessively noisy. The fluctuating magnetism due to the current alternations causes a chattering noise at the pole faces which rapidly increases with an increase of load on the magnet. In the present invention these objections are overcome by providing a permanent break or air space of fixed dimensions in the magnetic circuit independent of the variable air gap between the pole faces.

In the accompanying drawings which illustrate a structure embodying my invention, Figure 1 is an elevation view partly in section of an electromagnet; Fig. 2 is an end view of one section of the magnet; Fig. 3 is a sectional view as indicated by the section line 3-3 on Fig. 2; and Fig. 4 is a view similar to Fig. 2 but showing a modification.

As shown on the drawing, the electromagnet comprises two sections A and B relatively movable toward and from each other. Each section is formed with pole pieces 1 which extend into magnet coils 2. Fig. 1 shows two of such coils in section. The exciting coils 2 are preferably stationary being mounted in a suitable frame, and the sections A and B are movable toward and from each other. When the magnet coils are excited the two sections are drawn inward with the pole faces of the section B in contact with the opposing faces of the section A. Each section comprises a body portion 3 of brass or other non-magnetic material around which is placed a

laminated iron ring or sleeve 4, the projecting portions forming the poles of the magnet. Surrounding the iron is a sleeve 5 of brass or other non-magnetic material. 6 A fiber washer 6 is interposed between the upper end of the iron core 4 and the body 3 of the magnet.

The method of constructing and assembling the magnet is as follows: A ribbon or 10 thin strip of soft iron the proper width to form the magnet core 4 is tightly wound on the body portion 3, until the magnet core is of sufficient thickness. The outer sleeve or casing 5 is then heated and shrunk onto the 15 magnet. Holes 7 and 8 are then bored to receive the pins 7' and 8' which securely hold the several parts of the magnet in proper relative position. Portions of the magnet are also cut away to form projecting 20 pole pieces 1. In order to prevent residual magnetism the magnet core is provided with spaces or slots 9 which break the continuity of the magnetic iron circuit, so that when the current is cut off after the pole faces 25 have been brought together there is no residual magnetism to resist the separation of the magnet poles or to cause them to stick as it is usually termed. The slots 9 are formed in the following manner after the magnet has 30 been assembled:—Small holes 10 are drilled through the body portion 3 adjacent to the iron core 4 in order to admit the blade of a hack saw. A slot or kerf 9 is then cut with the hack saw through the magnet core. Each 35 of the sections A and B is preferably provided with two of these kerfs 9 which are located diametrically opposite each other. When the magnet is assembled the slots 9 in one section are placed 90° in advance of 40 those in the other section. In other words the four slots are 90° apart. With this method of construction and arrangement there is a slot 9 in each of the four magnet circuits. If preferred a slot 9 may be provided 45 between each pair of adjacent pole faces of one of the sections as illustrated in Fig. 4. In this case only one of the two magnet sections need be provided with slots. The arrangement shown in Fig. 2, however, 50 results in a somewhat stronger construction and requires a less number of bolts or rivets such as 7' and 8' to securely hold the parts in position. The holes 10 are bored through the body portion 3 in preference to the ring 55 5 in order to guard against any material weakening of the structure.

Fig. 4 shows a modified structure in which 60 six pole pieces are comprised in each section of the magnet, instead of four pole pieces as in the other figures. In this instance I have shown a slot 9 between each two adjacent poles, so that no slots are required in the opposing member. Obviously each member might comprise but three slots so that the 65 slots in the two members will alternate as

described in connection with the other views. The slots 9 may if desired be filled with any suitable insulating material, such as fiber.

It should be noted that the air gaps 9 have fixed dimensions, whereas in the usual constructions the air gap employed is only between the pole faces and varies with the relative position of the magnet and its armature or the movable sections of the magnet core.

An important feature of the present invention is the method of construction as heretofore described whereby the laminated iron portion of the magnet may be readily formed from sheet material and various parts of the magnet securely fastened together with no possibility of the parts becoming misplaced. In other words each of the sections A and B is a solid structure, the several parts rigidly and securely attached together so as to form practically an integral structure, which is not materially weakened by the formation of the slots 9.

In operation the magnet coils 2 which are fixed in relation to the members A and B, are energized to cause the said members to 90 be drawn upward until their pole faces are in contact. When the pole faces are thus in contact the magnet is practically noiseless. That is, the current alternations do not produce any material vibration and chattering 95 at the pole faces. When the magnet is de-energized its members are immediately separated as the air gaps 9 positively prevent any residual magnetism to oppose the action of the brake springs or other separating 100 means. Without such slots to break the continuity of the iron circuit, there is always more or less residual magnetism, the value of which varies widely depending upon the strength and direction of the energizing current at the instant the circuit is broken. If 105 an air gap or break in the magnet circuit is maintained by interposing non-magnetic material between the pole faces or otherwise preventing the latter from coming in contact, the magnet is noisy, the chattering noise depending largely on the load placed on the magnet and being excessive where the load is heavy. Also the non-magnetic material 110 is subject to wear and eventually permits the pole faces to come together, and thus allows the residual magnetism to assert itself. In the present invention these objections are overcome while at the same time the efficiency and also the mechanical strength of 115 the magnet are maintained.

I wish it to be understood that the present invention is not limited to the specific structure herein disclosed, but comprehends all such modifications and structures as come 120 within the terms and scope of the appended claim.

What I claim is:—

In an electromagnet, the combination of oppositely disposed members each compris- 125

ing a base an iron sleeve surrounding the

base and formed with projecting pole pieces,
said sleeves being formed with spaces in the
body of the ring between the pole pieces and
breaking the continuity of the magnetic path
between adjacent pole pieces, said spaces
being arranged to alternate in the said
members.

In testimony whereof, I have signed my
name to this specification in the presence of 10
two subscribing witnesses.

WILLIAM D. LUTZ.
